UNITED STATES PATENT OFFICE.

LANSING ONDERDONK, OF NEW YORK, N. Y., ASSIGNOR TO THE UNION
SPECIAL SEWING MACHINE COMPANY, OF CHICAGO, ILLINOIS, A
CORPORATION OF ILLINOIS.

OVERSEAMING-MACHINE.

No. 829,349.

Specification of Letters Patent.

Patented Aug. 21, 1906.

Application filed June 4, 1901. Serial No. 63,078.

To all whom it may concern:

Be it known that I, LANSING ONDERDONK, a citizen of the United States, residing at New York, in the county of New York, State 5 of New York, have invented certain new and useful Improvements in Overseaming-Machines, of which the following is a description, reference being had to the accompanying drawings and to the characters of reference marked thereon.

My invention relates to an improvement in sewing - machines, and particularly to machines for finishing the edges of fabrics, the object being to provide a sewing-machine 15 making a stitch which shall be ornamental, elastic, and serviceable in binding or finishing the edges of cut knit goods or other fabrics, which machine shall be capable of running at a high rate of speed with minimum amount 20 of noise and friction and in which the movements of the coöperating stitch-forming implements shall be simple forward and backward short movements with no complex sidewise or oscillatory movements.

The invention therefore consists in the matters hereinafter described, and referred to in the appended claims.

The invention is illustrated in the accompanying drawings, in which—

Figure 1 is a front view of a sewing-machine embodying my invention, the front covering-plate being removed to more clearly show the parts. Fig. 2 is a similar view taken from the rear of the machine. Fig. 3 is a top plan view with the top plate and overhanging arm removed. Fig. 4 is a view similar to Fig. 3, showing a slightly-different arrangement for supporting the looper and spreader. Fig. 5 is a perspective view showing the relation of the parts, certain of them being detached from their operating connections. Fig. 6 is a detail view showing the spreader in side and front elevation with a portion of the looper coöperating therewith. Figs. 7, 45 8, and 9 are detail views illustrating the manner of forming the stitch. Fig. 10 is a detail view illustrating the spreader and looper adjustments.

In the drawings, A represents the base of a 50 sewing-machine of the well-known "Union Special" type. B the overhanging arm or gooseneck, C the needle-lever, D the needle-bar carrying the needle 1, E the belt-wheel,

and F the eccentric connecting-rod through which connection is made from the driving shaft G to the needle-lever, all these parts being of the familiar construction. 55

The novel features of the present machine reside in certain features of construction, which will be hereinafter referred to. 60

Upon the driving-shaft G is mounted an eccentric H, which carries a crank I, embraced by the clamping-collar K on the lower end of the connecting-rod L, which at its upper end is freely pivoted by a ball-and-stud 65 connection M to the arm N of a bell-crank lever pivoted at O on the machine-frame and having a downwardly-extending arm P, carrying at its lower end a ball-stud Q, to which is attached in the usual manner the head R on 70 the end of the pitman S, which at its opposite end has a head T embracing a ball on the stud U, secured to the arm V, which is secured to the shank of the looper or looper-support W.

The looper a is herein shown provided with 75 the shank W, which passes through and is journaled in the bearing-block b, adjustably secured by slots and screws c d to the machine - frame, and to prevent longitudinal movement of the looper support or shank a 80 collar e is provided upon one side of the bearing-block, which on the other side the arm V is shown provided with a sleeved extension secured to the looper-supporting shaft or shank. The shape of the looper, 85 with its shank, is shown clearly in Figs. 1, 3, and 5 of the drawings, and it will be noted that the looper-shank outside of its supporting bearing-block extends to such position as that in the oscillation of the looper-supporting shaft the looper will swing from a point below the bed-plate up over the edge of the fabric being sewed and carry its thread in position to be engaged by the needle 1 in the descent of the latter, and it will be noted that 90 this oscillation of the looper is imparted to it regularly through the connections just described.

In Fig. 4 a slightly-different form of looper is shown, and the bearing-block b' is formed 100 as a part of the machine-frame and is not made adjustable in the manner shown in Fig. 3; but adjustment of the looper-supporting shaft or shank in or out is accomplished 105 by means of the screw f and slotted block g. This adjustment is shown in detail in Fig. 10,

in which the bracket supporting the looper-shaft is provided with a pin 100, passing through the block *g*, and adjustment is effected by means of the screw *f*, passing 5 through the open-ended slot 101. The means for operating the pitman *S*, however, and through it the looper-supporting shaft, will be understood to be the same in the construction shown in Fig. 4 as in that shown in Fig. 10 2 and 3. Coöoperating with the looper to regulate the slack is a thread-eyelet *h*, having its shank adjustably secured, by means of the screw *i*, within a socket on a portion of the machine, herein shown as the feed-dog-carrying 15 bar.

By referring to Figs. 5, 7, and 8 it will be noted that the looper has the open spring-eyelet *k*, whereby it is more easily threaded, and as it moves backwardly it will take up the slack 20 and help tighten up the stitch. After it gets to a certain point below the thread-eyelet *h* it will pull off from the spool. Thus the thread will be kept taut during the entire backward movement of the looper; but when it starts 25 forward there will be a slack between the adjustable eyelet *h* and the open eyelet *k* on the looper, this pull off of the thread in the backward movement to be utilized in the forward movement, preventing any strain upon the 30 thread in the forward movement of the looper.

To coöperate with the looper mechanism just described in forming the stitch illustrated in Figs. 7, 8, and 9 of the drawings, I 35 have provided a spreader or device for manipulating the needle-loop, which at the proper time catches the needle-loop below the goods, draws the thread to a point where the looper in its forward movement carries 40 its own thread through said needle-loop, the spreader backing out of said needle-loop at the proper time. The mechanism for operating this needle-thread-manipulating device or spreader is shown in Figs. 1, 3, and 5 and a 45 slight modification thereof in Fig. 4 and is substantially as follows: This spreader or loop-carrier *X* has its shank secured within a socket *l* on the cylindrical block or sleeve *m*, pivoted upon the bolt *n*, which passes through 50 the arm *Y*, forming a part of the stationary block *Z*, secured to the machine-bed. The block or sleeve *m* has a downwardly-extending arm *o*, provided with a projecting ball-stud *p*, to which is pivoted the head *q*, on one 55 end of the pitman *S'*, which at its opposite end is similarly attached by the head *r* to a stud *s* on the extension *C'* of the needle-lever. The parts are so timed with relation to each 60 other and to the movements of the needle as to make the stitch shown in Figs. 7, 8, and 9 of the drawings.

A modification of the manner of support and operating the spreader *X* is shown in Fig. 4, in which a bearing-block 2 is provided 65 through which the shank or supporting-shaft

of the spreader *X* passes, there being clamped on this shaft the sleeve 3, having a downwardly-extending arm 4, to which the pitman *S'* is operatively connected.

The trimming mechanism and mechanism 70 for throwing the same into and out of action form the subject-matter of an application filed on the 18th day of February, 1902, Serial No. 94,590.

Various minor modifications and changes 75 in the construction of the various parts of the machine may be made without departing from the spirit of my invention.

Having thus described my invention, what I claim, and desire to secure by Letters Pat- 80 ent, is—

1. A sewing-machine, comprising a reciprocating needle and mechanism for operating the same, complementary stitch-forming mechanism including a thread-carrying looper 85 mounted upon an oscillating support arranged to one side of and in rear of the needle, said looper being attached to its support and extending to a point in front of the needle, whereby it oscillates in a single plane from a 90 point in front of and upon the opposite side of the needle from the support, and below the fabric up over the edge into position, where its thread will be engaged by the needle in its descent, and a spreader or loop-carrier mounted upon an oscillating support, 95 which support is entirely in front of the needle and upon the opposite side thereof from the looper-support, said spreader being attached to its support and extending to the 100 rear of the needle and moving from a point in rear to a point in front of the needle to carry the needle-thread into position to be entered by the thread-carrying looper on its upward movement; substantially as de- 105 scribed.

2. A sewing-machine, comprising a reciprocating needle and mechanism for operating the same, complementary stitch-forming mechanism including a thread-carrying looper 110 mounted upon an oscillating support arranged to one side of and in rear of the needle, said looper being attached to its support and extending in a plane to the opposite side and in front of the needle, whereby it oscillates in 115 a single plane from a point in front of and upon the opposite side of the needle from the support, and below the fabric up over the edge into position, where its thread will be engaged by the needle in its descent, and a spreader or loop-carrier mounted upon an oscillating support, 120 which support is entirely in front of the needle and upon the opposite side thereof from the looper-support, said spreader being attached to its support and extending to the rear of the needle and moving from a point in rear to a point in front of the needle to carry the needle-thread into position to be entered by the thread-carrying 125 looper on its upward movement, said looper 130

and spreader supports being arranged substantially horizontally and inclined to the line of feed; substantially as described.

3. In a sewing-machine, having a reciprocating needle, a complementary stitch-forming mechanism including a looper arranged in front of said needle, and having a shank, extending diagonally across the line of feed, an oscillating support arranged at an angle to the line of feed, and in rear of the needle to which the shank is attached, and connections between said oscillating support and the driving-shaft of the machine, a spreader arranged in front of the needle, an oscillating support upon which the same is mounted, the axis of said oscillating support being at an angle to the line of feed and so arranged that in the movement of the spreader, it will cross the path of movement of the looper; substantially as described.

4. In a sewing-machine having a reciprocating needle and complementary stitch-forming mechanism, including an oscillating looper, a support for said looper arranged at an angle to the line of the feed, and in rear of the needle, and connections between the looper and the driving-shaft of the machine, a spreader arranged in front of the needle, an oscillating support upon which the same is mounted, the axis of said oscillating support being at an angle to the line of feed and so arranged that in the movement of the spreader it will cross the path of movement of the looper, said oscillating looper being adjustable upon its support, substantially as described.

5. In a sewing-machine having a reciprocating needle, a complementary stitch-forming mechanism including a looper arranged in front of said needle and having a shank extending diagonally across the line of feed, an oscillating support arranged at an angle to the line of feed and in rear of the needle, to which support said shank is attached, and connections between said oscillating support and the driving-shaft of the machine, a spreader arranged in front of the needle, an oscillating support upon which the same is mounted, the axis of said oscillating support being at an angle to the line of feed and so arranged that in the movement of the spreader it will cross the path of movement of the looper, said oscillating looper-support being

adjustable in the direction of its length, that is transversely of the machine; substantially as described.

6. In a sewing-machine having a thread-carrying looper moving from below the plane of the fabric up over the edge thereof, and complementary stitch-forming mechanism, including a needle and a spreader to take the loop of needle-thread and carry it into position to be engaged by the looper, an adjustable thread-guide arranged in a horizontal plane which intersects the path of movement of the looper and adjustable at right angles to the path of movement of said looper, whereby as the looper moves backward below the plane of the thread-guide, it will take up the slack in the looper-thread and help tighten the stitch and pull off from the spool, but as it moves forwardly will cause a slack thread and lessen the strain; substantially as described.

7. A sewing-machine comprising a reciprocating needle and mechanism for operating the same, complementary stitch-forming mechanism including a thread-carrying looper mounted upon an oscillating support arranged to one side of and in rear of the needle, said looper being attached to its support and extending to a point in front of the needle, whereby it oscillates in a single plane from a point in front of and upon the opposite side of the needle from the support, and below the fabric up over the edge into position where its thread will be engaged by the needle in its descent, and a spreader or loop-carrier mounted upon an oscillating support, and moving from a point in rear to a point in front of the needle to carry the needle-thread into position to be entered by the thread-carrying looper on its upward movement, a main driving-shaft and connections between the driving-shaft and the looper-support including a pitman operated from the driving-shaft, and ball-joint connections between the ends of the pitman and said looper-support; substantially as described.

In testimony whereof I affix my signature in presence of two witnesses.

LANSING ONDERDONK.
